(57) **CLAIM**

The ornamental design for a display screen with graphical user interface, as shown and described.

DESCRIPTION

The FIGURE is a front view of a display screen with graphical user interface showing our new design.

The broken lines depicting the remainder of the display screen with graphical use interface show features that form no part of the claimed design.

The broken line depicting the display screen, and all other broken lines illustrating the remainder of the graphical user interface, form no part of the claimed design.

1 Claim, 1 Drawing Sheet
